UNITED STATES PATENT OFFICE.

GEORGE H. FORSYTH, OF CHICAGO, ILLINOIS, ASSIGNOR TO FORSYTH BROTHERS COMPANY, OF CHICAGO, ILLINOIS, A CORPORATION OF ILLINOIS.

SASH-BALANCE.

1,103,496.

Specification of Letters Patent. Patented July 14, 1914.

Application filed November 19, 1906. Serial No. 344,033.

To all whom it may concern:

Be it known that I, GEORGE H. FORSYTH, a citizen of the United States, residing at Chicago, in the county of Cook and State 5 of Illinois, have invented certain new and useful Improvements in Sash-Balances, of which the following is a specification.

This invention relates to sash balances and more particularly to sash balances of that 10 type wherein an actuating spring or weight constituting the power agent of the device is wound up or tensioned by the downward movement of the sash so as to counteract the gravity of the latter and raise or assist in 15 raising the sash when the latter is free to move upwardly.

It is the object of the invention to produce a simple and efficient device of this character compactly arranged and assembled in a manner to economize space; to so organize the 20 parts that the stresses are equalized in and through the mechanism of the balance itself, preferably in the spring and its connections, so as to pull equally and uniformly on both 25 sides of the sash; and to provide an improved device wherein the spring may be tensioned without requiring the removal of the sash from its guides.

My invention has been more particularly 30 designed for use in connection with the windows of railway cars and especially those employing hollow sheet metal window sash; although it will be evident that the device is capable of general application and to sash 35 of any type of construction.

In one arrangement and disposition of the device the sash balance is carried by the upper transverse bar of the sash, and operates through the agency of rack bars 40 diagonally disposed on the sash guides coöperating with spring or weight-actuated gears or pinions on the opposite ends of the sash balance spindle. In another application of the invention, however, the balance may be 45 otherwise connected to the sash; and in all forms it operates to automatically counteract any lack of uniformity or equality of strain in the sash connections.

My invention is capable of employing torsion 50 springs of either relatively large or small diameter, according to the space permitted therefor by the window casing, by a simple interchangeability in the relative diameters of the springs and the gears or 55 pinions through which the torsional effect of

the springs is transmitted to the racks of the guides.

My invention will be readily understood when considered in connection with the accompanying drawings, showing practical 60 mechanical embodiments thereof, in which,—

Figures 1 and 2 are vertical sectional views through the upper portion of the window sash and the superimposed sash balance; said views differing only in showing different 65 modes of connection between the casing preferably employed in connection with sash balances and the upper transverse bar of the sash; Fig. 3 is a side elevational view of the parts shown in Fig. 2; Fig. 4 is a plan view, 70 enlarged, of one form of sash balance, in section through the casing of the balance and the guides thereof; Fig. 5 is a detail fragmentary view in elevation of the means for tensioning the spring of Fig. 4; Fig. 6 is a 75 view similar to Fig. 4 of a modified construction of sash balance; Fig. 7 is a group view in end elevation of individual parts employed in the mechanism of Fig. 6; Fig. 8 is an elevational view of a simple form of the 80 invention, showing other devices for connection to the sash; and Fig. 9 is an edge view of Fig. 8.

Referring first to Figs. 1 to 5, inclusive, 10 may designate the vertical angle-strips forming 85 between them the lateral guides of a hollow sheet metal sash indicated at 11. 12 indicates in Fig. 1 a rectangular sheet metal casing for the sash balance shown as formed integral with the upper transverse bar of the 90 sash and superposed thereon, said casing being also indicated as of somewhat greater width than the width of the sash bar and is guided at its ends by vertical angle-strips 13 constituting superposed continuations of the 95 guide-strips 10. In Figs. 2 and 3 the sash balance casing, instead of being formed integral with the upper transverse bar of the sash, is made separate and is attached to said bar by means of depending integral 100 tongues 14 passed through spaced apertures in the top of the bar and secured by connecting-strips 15 and a screw-bolt 16.

Referring now to the constructional features of the balance proper shown in detail 105 in Figs. 4 and 5, 17 designates as an entirely a spindle in the casing 12, said spindle carrying on its opposite ends pinions 18 meshing with diagonally disposed vertical rack-bars 19 secured to or integral with cor- 110

responding transverse diagonally disposed guide-strips 13. This sectional spindle comprises end sections 17^a and 17^b on which the pinions 18 are directly mounted, an intermediate section 17^c, and an enlarged spring-supporting section 17^d between the sections 17^b and 17^c. The sections 17^b and 17^c are provided on their inner opposed faces with disks 20 and 21, respectively, to the inner faces of which are attached the opposite ends of the coiled torsion spring 22, said spring encircling the intermediate guiding and supporting section of the spindle 17^d which is loosely or rotatably supported at its ends in the opposed faces of the disks 20 and 21. Fast on the opposite end of the intermediate section 17^c of the spindle is a conical worm-wheel 23 engaged by a worm 24 disposed transversely thereof, said worm being partially housed in a recess in the adjacent face of a disk or block 25 carried by the adjacent end of the end section 17^a of the spindle, whereby said worm forms in effect a coupling between the sections 17^a and 17^c of the spindle, causing said sections to rotate together in the operation of the balance, but permitting a relative turning movement therebetween by turning the worm, for which latter purpose the outer face of the worm is provided with a transverse groove 26, and to permit the application of a screw driver thereto, the inner side of the disk 25 is cut away sufficiently, as indicated at 27 (Fig. 5). By virtue of the fact that the gears 18 engage racks on opposite sides of the end guides of the balance casing, an upward or downward movement of the latter accompanying the raising or lowering of the window imparts rotation in opposite directions to the spindle section 17^b on the one hand and the coupled sections 17^a and 17^c on the other hand, which, in the arrangement shown, winds up or tensions the spring 22 on the downward movement of the window, the reaction or torsional expansion of the spring imparting a climbing effect to the pinions when the sash moves upwardly, thereby raising or assisting in raising the sash. The side wall of the casing is provided with an opening 28 for a screw-driver opposite the front end of the worm 24, through which the spring may be readily tensioned to the necessary extent by simply turning the screw;

55 The same general principle of sash balance is carried out in the somewhat modified construction illustrated in Figs. 6 and 7. In this construction a sectional spindle designated as an entirety by 29 is also employed, the end sections connected to the gears 18 being designated by 29^a and 29^b, the main intermediate section being designated by 29^c, and the spring guiding and supporting section being designated by 29^d, the ends of the latter section being loosely mounted in

the adjacent ends of the sections 29^b and 29^c, as shown. Integral with or fast on the intermediate section 29^c is a bevel pinion 30 engaged by a companion bevel pinion 31 rotatively mounted in a suitable bearing bracket 32 secured to the side wall of the casing, said pinion 31 having in its outer face a groove 33 for the application of a screw-driver, said groove being located opposite a registering aperture 34 in the wall of the casing. Embracing the section 29^a and having its ends secured in the sections 29^b and 29^c is a torsion spring 35. The sections 29^a and 29^c of the spindle are detachably coupled so as to permit tensioning of the spring when desired without removal from the casing, by the following means. Pinned or keyed to the inner end of the spindle section 29^a is a sleeve 36, the outer portion whereof is externally squared, as shown at 36^a (Fig. 7), while its inner portion is externally circular, as shown at 36^b. An externally squared sleeve 37 surrounds and is pinned or keyed to the meeting end of the spindle section 29^c. Slidably mounted upon the sleeves 36 and 37 is a squared sleeve 38 provided with an annular peripheral groove 38^a. A compression spring 39 surrounding the sleeve 37 bears at one end against a bearing 18^a and by contact with the adjacent end of the sleeve 38 tends to force the same over the squared portion 36^a of the sleeve 36, whereby the sections 29^a and 29^c of the spindle are normally coupled. A slot 40 is formed in the side wall of the casing opposite the groove 38^a, so that by inserting a suitable tool therethrough into engagement with the slot 38^a the sleeve 38 may be slid inwardly against the spring 39 until its outer end disengages the squared portion 36^a and engages the rounded portion 36^b of the sleeve 36, whereupon, by simultaneously applying a screw-driver to the pinion 31, the spring may be tensioned to the desired strength. Upon releasing the sleeve 38, the spring 39 at once forces it into coupling engagement with the squared portion of the co-operating sleeve 36, thereby re-establishing the continuity of the spindle. In its manner of operation this form of balance is identical with that already described and shown in Figs. 4 and 5, the downward movement of the sash tending to wind up or tension the spring 35; the expanding movement of said spring taking place during and partially or wholly effecting the opposite or rising movement of the sash.

56 In Figs. 8 and 9 I have illustrated another embodiment of the principle of the invention which permits a considerable simplification of the mechanism, but which embodies the features of the equalization of the stresses at both ends of the balance by distributing the same through the spring and its connections. In this embodiment, 41

may designate the opposing sides of the frame or casing, to which are secured supporting brackets 42 and 43, the former of which has a socket 44 forming a bearing for one end of a spindle 45, the other bracket 43 having a similar socket open on its upper side, as indicated at 46, to admit the other end of the spindle. Loose on the spindle 45 at its opposite ends are pulleys 47, to 10 which are secured straps 48 adapted to be oppositely wound thereon, and connected to the top bar of the sash 11 as by means of staples 49 suitably secured to the latter. Enveloping the spindle 45 and anchored at its 15 opposite ends in the adjacent faces of the pulleys 47 is a torsion spring 50. By reason of the fact that one of the pulleys 47 is connected to one end of the spring and the other to the other end of the spring, the 20 stress imparted by the spring acts at both ends of the latter independently on the pulleys, and therefore takes up automatically any slack or lack of equality of tension in or upon the straps 48, and insures an equal 25 pull on both sides of the sash. This latter result is obviously attained also in the constructions disclosed in the embodiments of the invention previously described.

It will be noted that in the construction 30 set forth in Figs. 4 and 5 a spring of comparatively large diameter is employed in connection with relatively small gear-wheels 18; while in the construction disclosed in Figs. 6 and 7 a spring of relatively 35 small diameter is employed in connection with relatively large gears. Where there is room for a relatively wide sash balance the construction of Figs. 4 and 5 may be employed, the larger diameter of spring permitting a relative diminution in the diameter of the gears; whereas, where the lateral 40 space for the sash balance mechanism is limited, a smaller spring may be employed and rendered effective through the employment 45 of relatively large gears, which obviously do not require as many turns to tension the spring as do the relatively smaller gears.

The capability of the mechanism to permit 50 tensional adjustment of the spring without necessitating any removal of the mechanism from its casing or from the window constitutes an important feature of the invention; and it will be evident that the 55 structural features herein disclosed may be considerably modified and varied by those skilled in the art without departing from the principle or sacrificing any of the advantages of the invention.

60 I claim:

1. In a sash balance, the combination of 65 a sash, a torsion spring, reversely rotatable power-transmitting members connected to and independently actuated by the opposite ends of said spring respectively, and con-

nections between said power-transmitting members and the sash whereby an equalization of the action of said spring on said sash is secured, substantially as described.

2. In a sash balance, the combination of 70 a movable sash and its frame, a torsion spring, and reversely rotatable members fastened to opposite ends of said spring and operating along the vertical walls of said frame for actuating the sash, substantially 75 as described.

3. In a sash balance, the combination of 80 a movable sash and its guides, a torsion spring, and means for equally balancing said sash including oppositely rotatable members 85 acted upon by the opposite ends of said spring and oppositely rotatable in planes transverse the axis of the spring, substantially as described.

4. In a construction of the character described, the combination of a sash frame, a sash movable in said frame, a torsion spring, independently operable power-transmitting members secured to opposite ends of 90 said spring in engagement with the frame and adapted to cause an equal balancing of 95 said sash, substantially as described.

5. In a sash balance, the combination with 100 a sectional spindle having an interposed torsion spring and a coupling member, the latter constituting also tensioning members for said spring, of gears on the ends of said spindle, and diagonally disposed racks engaged by said gears, substantially as described.

6. In a sash balance, the combination with 105 a sectional spindle and an interposed torsion spring, of a coöperating worm-wheel and worm on adjacent ends of adjacent sections of the spindle, said worm-wheel and worm constituting tensioning members for the spring and a coupling for the spindle sections, gears on the ends of said spindle, and diagonally disposed racks engaged by 110 said gears, substantially as described.

7. In a sash balance, the combination with 115 a movable sash and its frame, of a torsion spring, a pair of oppositely rotatable pinions connected one to each end of the spring, and oppositely facing racks carried by the frame each in mesh with one of the pinions, substantially as described.

8. In a sash balance, the combination with 120 a movable sash and its frame, of a torsion spring, a pair of oppositely rotatable pinions connected one to each end of the spring, oppositely facing racks carried by the frame each in mesh with one of the pinions, and an adjustable connection between one end of the spring and its pinion 125 whereby to regulate the tension of the spring without disturbing its sash balancing function, substantially as described.

9. In a sash balance, the combination with 130 a movable sash and its frame, of a tor-

sion spring, rotatable members connected to the ends of the spring and engaging the frame, and a gear connection between the end of the spring and one of the rotatable members whereby to angularly adjust the same, substantially as described.

10. In a sash balance, the combination with a movable sash and its frame, of a torsion spring, rotatable members engaging the frame, and a connection between one end of the spring and one of the driving members whereby to angularly adjust the same to regulate the tension of the spring, said connection comprising a spindle arranged axially of the spring, a worm-wheel thereon, a disk mounted on the shaft of the rotatable member, and a worm journaled in the disk in mesh with the worm-wheel, the worm provided with exteriorly accessible 15 means to rotate the same, substantially as described.

11. In a sash balance, the combination of

a sash, a torsion spring, reversely rotatable power-transmitting members connected to and independently actuated by the opposite 25 ends of said spring respectively, and connections between said power-transmitting members and the sash whereby an equalization of the action of said spring on said sash is secured, and means for adjusting the 30 tension of the spring, substantially as described.

12. In a sash balance, the combination of a movable sash and its frame, a torsion spring, and reversely rotatable members fastened to opposite ends of said spring and operating along the vertical walls of said frame for actuating the sash, and means for adjusting the tension of the spring, substantially as described. 35
